(57) **CLAIM**

We claim the ornamental design for a cleaning assembly, as shown and described.

DESCRIPTION

FIG. 1 is an isometric view of a cleaning assembly in a first orientation according to a first embodiment;

FIG. 2 is a front side view of the cleaning assembly illustrated in FIG. 1 in the first orientation;

FIG. 3 is a rear side view of the cleaning assembly illustrated in FIG. 1 in the first orientation;

FIG. 4 is a side view of the cleaning assembly illustrated in FIG. 1 in the first orientation;

FIG. 5 is a side view, which is opposite the side view of FIG. 4, of the cleaning assembly illustrated in FIG. 1 in the first orientation;

FIG. 6 is a top side view of the cleaning assembly illustrated in FIG. 1 in the first orientation;

FIG. 7 is a bottom side view of the cleaning assembly illustrated in FIG. 1 in the first orientation;

FIG. 8 is an isometric view of a cleaning assembly illustrated in FIG. 1 in a second orientation;

FIG. 9 is a front side view of the cleaning assembly illustrated in FIG. 1 in the second orientation;

FIG. 10 is a rear side view of the cleaning assembly illustrated in FIG. 1 in the second orientation;

FIG. 11 is a side view of the cleaning assembly illustrated in FIG. 1 in the second orientation;

FIG. 12 is a side view, which is opposite the side view of FIG. 4, of the cleaning assembly illustrated in FIG. 1 in the second orientation;

FIG. 13 is a top side view of the cleaning assembly illustrated in FIG. 1 in the second orientation;

(Continued)

FIG. 14 is a bottom side view of the cleaning assembly illustrated in FIG. 1 in the second orientation; FIG. 15 is an isometric view of a cleaning assembly in a first orientation according to a second embodiment; FIG. 16 is a front side view of the cleaning assembly illustrated in FIG. 15 in the first orientation; FIG. 17 is a rear side view of the cleaning assembly illustrated in FIG. 1 in the first orientation; FIG. 18 is a side view of the cleaning assembly illustrated in FIG. 15 in the first orientation; FIG. 19 is a side view, which is opposite the side view of FIG. 18, of the cleaning assembly illustrated in FIG. 15 in the first orientation; FIG. 20 is a top side view of the cleaning assembly illustrated in FIG. 15 in the first orientation; and, FIG. 21 is a bottom side view of the cleaning assembly illustrated in FIG. 15 in the first orientation. The broken lines in the drawings form no part of the design to be patented.
